COMBINED FLASH LIGHT, WHISTLE, COMPASS, AND KEY CHAIN HOLDER

George L. Bautsch, 3520 Chase St., La Crosse, Wis.

Filed Mar. 17, 1961, Ser. No. 64,477

Term of patent 7 years

(Cl. D48—24)

FIGURE 1 is a perspective view of a combined flash light, whistle, compass and key chain holder showing my new design with the chain shown in broken lines for illustrative purposes only;

FIGURE 2 is an end elevation thereof;

FIGURE 3 is an end elevation thereof as seen from the opposite end of FIG. 2; and

FIGURE 4 is a bottom plan view.

I claim:

The ornamental design of a combined flash light, whistle, compass, and key chain holder, as shown and described.
